5 Claims. (Cl. 315—8.6)

This invention relates to magnetron-type electron discharge tubes and to improvements in the construction and operation of such tubes, particularly as noise-generators.

One form of magnetron tube, to which the principles of the invention apply, comprises a multi-position device and includes an electrode assembly which includes an elongated central cathode and a plurality of groups of elongated electrodes surrounding the cathode and secured together at their opposite ends by means of insulating end disks or plates. All of the electrodes are oriented substantially parallel to each other. An external cylindrical magnet surrounds the tube envelope and electrode assembly.

In operation of this type of tube, a beam of current flows from the central cathode and is urged to rotate around the tube under the influence of crossed electric and magnetic fields. The beam may remain static at one group of electrodes, or it may be switched from position to position by the application of proper potentials to selected ones of the tube electrodes.

If the beam is static, an output current is obtained, the magnitude of which is determined by the various operating parameters. However, for any one set of operating conditions, optimum utilization of the electron beam and maximum output current, particularly noise output, are not achieved.

The principles and objects of the present invention are concerned with the provision of an improved arrangement for a multi-position magnetron beam tube and an improved circuit for operating the same whereby favorably high output current and high noise output are obtained.

In brief, a multi-position magnetron tube embodying the invention comprises, in a suitable envelope, an electrode assembly including a central longitudinally elongated cathode electrode surrounded by groups of longitudinally elongated electrodes which are adapted to form and receive an electron beam from the cathode. Each group of electrodes includes an output or target electrode from which an output signal may be derived and a spade electrode which may be used to form and hold an electron beam on its associated target electrode. A cylindrical permanent magnet surrounds the tube and provides the required longitudinal magnetic field. In operation of the tube, an electron beam is not switched from position to position, but is maintained in a static condition, flowing simultaneously to two opposed target electrodes which are coupled together and from which the desired output signal is derived. This arrangement provides more efficient utilization of the electron beam and increased noise signal output.

The invention is described in greater detail by reference to the drawing, wherein:

FIG. 1 is a sectional view of a multi-position magnetron tube used in practicing the invention;

FIG. 2 is a schematic representation of the tube of FIG. 1 and a circuit embodying the invention;

FIG. 3 is a schematic representation of a modification of the circuit of the invention; and

FIG. 4 is a schematic representation of another modification of the circuit of the invention.

The principles of the invention are applicable to mag-

2

netron tubes and, particularly, to a multi-position type 6700 magnetron beam switching tube which is shown as tube 10 in FIGS. 1 and 2. This type of tube is cylindrical in form and includes an envelope 12 which contains a central longitudinally elongated cathode 14 and ten groups of electrodes spaced radially equidistantly from the cathode and surrounding the cathode. Each group of electrodes includes a generally U-shaped elongated spade electrode 16 and a generally L-shaped target electrode 18 positioned so that each target occupies the space between adjacent spade electrodes. Each spade electrode serves to form and hold an electron beam on its corresponding target electrode. A type 6700 tube generally includes rod-like switching electrodes; however, since these electrodes are not used in practicing the invention, they are not shown in the drawing. The tube 10 also includes a cylindrical hollow magnet 22 surrounding the envelope and providing an axial magnetic field which is utilized in conjunction with electric fields within the tube to control electron beam flow.

In the circuit of the invention shown in FIG. 2, the tube 10 is shown schematically with its electrodes arrayed in linear form. The electrode and circuit arrangement are such that a double electron beam is formed and electrons flow from the cathode to two opposed groups of electrodes including the targets 18' which are assumed to be at the "0" and "5" positions or groups of electrodes in tube 10. In the circuit, the spade electrodes 16' associated with targets 18' are electrically connected by a suitable lead 24. Similarly, the targets 18' at the same positions are connected together by a lead 26 which is coupled through a load resistor 28 both to ground and to a source of positive D.C. potential. An output terminal 30 is also connected to the two targets 18'. All of the other electrodes are electrically connected together in any suitable fashion by leads 32, 34, and 36 so that, electrically, they comprise a single unit.

The relative potentials employed with the tube 10 to obtain two electron beams are as follows. The cathode is coupled to a D.C. potential V_C which is negative with respect to ground; the opposed "0" and "5" spades are coupled to a D.C. potential V_T which is positive with respect to the cathode; and all other electrodes are coupled to a D.C. potential V_0 which is made highly positive with respect to the cathode. In one operating circuit, V_T was about 75 volts positive, V_C was about 75 volts negative, V_S was about 100 volts negative, and V_0 was about 280 volts positive.

In operation of the circuit of FIG. 2, electrons emitted by the cathode 14 are divided into two beams with one beam flowing to each of the targets 18'. This current flow is effected by the electrode connections and by the relative potentials, particularly the negative potentials in the spade electrodes 16'.

Alternative arrangements for operating the tube 10 are shown in FIGS. 3 and 4. Since only the "0" and "5" electrode connections are modified, only these are shown and the others are omitted. According to these alternatives, the spade electrodes at the "0" and "5" positions have pulses applied to them, rather than the constant D.C. source shown in FIG. 2. In FIG. 3, a source 38 of negative pulses of about 100 volts in amplitude has its output 40 coupled to both spade electrodes 16' so that both spade electrodes are pulsed negative at the same time and noise output is obtained during this period. In FIG. 4, a flip-flop pulse source 42 is provided having a single input 44 and two outputs 46 and 48, one of which is connected to the "0" spade, the other of which is connected to the "5" spade. With this arrangement, the "0" and "5" spades are alternatively pulsed nega-

tive and noise output is obtained alternately from the target electrodes 18'.

The present invention thus provides a novel circuit arrangement for operating a magnetron beam switching tube. To the extent that this type of operation can be compared with current flow to a single output electrode, under similar operating conditions, the present invention provides greater noise output over a wider frequency range.

What is claimed is:

1. A double beam noise-generating circuit including a magnetron beam switching tube of the type utilizing crossed electric and magnetic fields, said tube having a cathode and a plurality of groups of electrodes surrounding said cathode; each group including a target electrode which receives an electron beam and produces an output signal therefrom, and a spade electrode which holds an electron beam on its associated target electrode; means providing a longitudinal magnetic field in said tube; a pair of oppositely disposed spade electrodes being connected together and to a source of negative potential, the target electrodes associated with said spade electrodes being coupled together to an output terminal and to a source of positive D.C. potential, said cathode being coupled to a negative D.C. potential, all of the

other electrodes being connected together and to a source of positive D.C. potential, the aforesaid electrode connections causing electrons emitted by said cathode to form two beams which flow one to each of the pair of oppositely disposed target electrodes associated with said pair of oppositely disposed spade electrodes whereby high noise current output is obtained.

2. The circuit defined in claim 1 wherein the potential applied to said oppositely disposed spade electrodes is more negative than the potential applied to said cathode.

3. The circuit defined in claim 1 wherein the negative potential coupled to said oppositely disposed spade electrodes is a D.C. potential.

4. The circuit defined in claim 1 wherein the source of negative potential coupled to said oppositely disposed spade electrodes is a source of negative pulses.

5. The circuit defined in claim 1 wherein the source of negative potential coupled to said oppositely disposed spade electrodes is a flip-flop having a single input and two outputs coupled one to each of said spade electrodes.
